UNITED STATES PATENT OFFICE.

MORRIS BERNHARD, OF NEW YORK, N. Y., ASSIGNOR TO DREYFUS BROTHERS, OF SAME PLACE.

DESIGN FOR A PENDANT.

SPECIFICATION forming part of Design No. 15,746, dated January 27, 1885.

Application filed November 25, 1884. Term of patent 7 years.

To all whom it may concern:

Be it known that I, MORRIS BERNHARD, of the city, county, and State of New York, have produced a new and original Design for Pendants, of which the following is a specification.

Reference is to be had to the accompanying drawing, forming a part of this specification, in which a face view of my new design for pendants is shown.

10 A slung ruff or tuft, A, is provided on the upper end of an inverted-cone-shaped drop or pendant, B, on the lower or smaller end of which a slung ruff or tuft, C, is secured, of about the same size as the tuft A. From the 15 tuft C two beads, D, are suspended by means of cords E. A loop, F, is secured on the top of the tuft A.

I claim—

1. The herein-described design for pendants, consisting of an inverted conical drop 20 or pendant having a tuft or slung ruff at each end and two beads suspended by cords from the lower tuft, substantially as set forth.
2. The herein-described design for pendants, consisting of an inverted conical drop 25 or pendant having a tuft or slung ruff at each end, a loop at the upper tuft, and two beads suspended by cords from the lower tuft, substantially as set forth.

MORRIS BERNHARD.
